UNITED STATES PATENT OFFICE.

RICHARD BRYANT WARD, OF SAN MARCOS, TEXAS, ASSIGNOR OF ONE-
THIRD TO NAPOLEON L. CAMP, OF SAN MARCOS, TEXAS.

HINGE-GAINER.

SPECIFICATION forming part of Letters Patent No. 695,355, dated March 11, 1902.

Application filed October 24, 1901. Serial No. 79,863. (No model.)

To all whom it may concern:

Be it known that I, RICHARD BRYANT WARD, a citizen of the United States, residing at San Marcos, in the county of Hays and State of Texas, have invented a new and useful Hinge-Gainer, of which the following is a specification.

This invention relates to certain improvements in devices of that class employed for cutting a gain or mortise in a door-jam or door for the reception of a hinge.

The object of the invention is to provide an improved machine or tool in which all of the parts may be readily and accurately adjusted to cut recesses of different width, length, and depth, as more fully described hereinafter.

In the accompanying drawings, Figure 1 is a perspective view of a hinge-gainer constructed and arranged in accordance with my invention. Fig. 2 is a sectional plan view of the same on the line 2 2 of Fig. 4. Fig. 3 is a longitudinal sectional elevation of the device on the line 3 3, Fig. 4. Fig. 4 is a transverse sectional elevation of the device on the line 4 4, Fig. 3. Fig. 5 is a sectional plan view showing a portion of the same on the line 5 5, Fig. 3. Fig. 6 is a detached perspective view of one of the end cutting knives or chisels. Fig. 7 is a transverse sectional elevation of a portion of the device on the line 7 7, Fig. 2.

Similar numerals of reference are employed to designate corresponding parts throughout the several figures of the drawings.

10 10 designate a pair of parallel guiding-bars on which are arranged a pair of longitudinally-adjustable carriages 11 and 12, said carriages forming supports and guides for carrying-bars 13, to which the end knives or chisels 14 are secured. The knives or chisels 14 are provided with lower cutting edges of any desired length, and the blades are secured to their carrying-bars by one or more screws 15. The bars 13 are rectangular or polygonal in cross-section and are adapted to 40 correspondingly-shaped guiding-openings in said carriages, and at the upper end of each bar is an enlarged head 17, which may be struck by a mallet to effect the end cuts. Projecting inwardly from each bar is a lug 18, 45 against the under side of which bears a suitable spring 19, the lower end of said spring

being secured at 20 to the carriage and its upper free end being yieldably engaged with the under side of said lug and serving to return the same to the initial or raised position 55 and withdraw the cutting-blade from contact with the wood after each operation.

On the outer end of each of the carriages is a pair of slotted bars 21, horizontally disposed and adjustable lengthwise, a thumb-screw 22 6c being passed through each of the slots and extending into the carriage, so that said arms may be locked in any position to which they may be adjusted. The bars or arms 21 are arranged in pairs on each carriage, and to the 65 outer ends are secured vertically-disposed and slotted guideways 23, adapted for the reception of the carrier 24 of a rear cutting knife or chisel 25, the upper end of said carrier being provided with a striking-head 26. This 70 adjustment permits of the movement of the rear cutting-chisel to any desired distance from the carriages, and the degree of adjustment may be ascertained and regulated by suitable gages 27, arranged on the outer ends 75 of the carriages and provided with suitable slots 28, through which pass thumb-screws 29 for locking the gages in an adjusted position. The face of each gage-bar 27 is preferably provided with a measuring-scale, as indicated at 80 31. The carriages may be adjusted from or toward each other for any desired distance on the guiding-bars 10, and when so adjusted may be locked in position by screws 32, which pass through the front portions of the carriage and at their inner ends impinge against the rear wall of a longitudinal groove 33, formed in the face of one of said guiding-bars.

At the front of the carriages 11 and 12 are 90 secured brackets 34, each bracket being provided with vertically-disposed spaced lugs 35, having alining vertical openings for the reception and guidance of adjusting-screws 36, the lower ends of which are secured to rectangular guiding-boxes 37. The guiding-boxes are held from any lateral or longitudinal play by vertical plates 38, which are secured to or formed integral with said boxes and bear against one face of the lugs 35. To 100 provide for the vertical adjustment of the boxes, a nut 39 is placed in the recess or

openings between each pair of vertical aligned lugs 35, said nut engaging with threaded bolts 36 and having a milled or roughened periphery, by which it may be readily turned to adjust the boxes any desired distance.

In boxes 37 is guided a bar 40, which extends parallel to the guiding-bars 10. This bar is secured at its opposite ends to a horizontally-disposed bar 41 by a bracket 42 at each end, or, as shown in Fig. 7, the two bars may be formed integral. To the bar 41 is secured a horizontally-disposed guiding-plate 42', having at one end an inclined notch 46 cut in its under surface for the reception of the tapering longitudinal edge of a mortising-chisel 45, and at intervals in the bar are similar notches 46, in which may be placed the inclined edges at the opposite sides of chisels of different width. The mortising-chisels are provided with a forward cutting edge 47, as usual, and side cutting edges 44 are also placed on said chisel for the purpose of making a cleaner cut and at the same time to afford a guiding means for the chisel during the cutting operation. The outer end of the chisel is preferably provided with a striking-head 48, as illustrated in Fig. 1.

The chisel is held against the plate 42 by a bottom carrying-plate 50, which may be adjusted from and toward the plate 42 by thumb-screws 51 in order to permit of the introduction between said plates of chisels of different thickness.

It will be seen that by suitably adjusting the nuts 39 the chisel may be raised or lowered to any desired extent to cut mortises of different depth for the accommodation of either light or heavy hinges.

In addition to the adjustment by the bolts 36 and nuts 39 the lower carriage is held in place by an end plate 52, secured at the outer end of the carriage 11 and provided with vertical slots 53 and 54 to permit of its vertical adjustment with respect to said carriage.

Through the slot 53 passes a guide-block 55, projecting from the end of the carriage, or, if desired, a thumb-screw may be substituted for said guiding-block. A second thumb-screw 56 passes through the slot 54 and permits of the locking of the plate in any position to which it may be adjusted. The lower portion of the plate is extended laterally and at its outer end is secured by thumb-screws 57 to a block 58, carried by the lower chisel-

guide. The plate is further provided with openings 58', through which said thumb-screw may pass to the openings in the block 58 when it is desired to adjust the relative positions of the plate and block. Through the lower supporting-plate 50 extends a thumb-screw 60, which may be turned into locking engagement with the under side of the mortising-chisel 45 when the device is not in use.

In using the device the various parts are first adjusted to form a cut of the required size and depth. The end chisels are then tapped with a mallet or other tool, and the rear

chisel 25 is in like manner forced down to the required depth. The mortising-chisel 45 is then forced in by mallet blows to remove the chip.

In some cases, as where an exceptionally small cut is to be made, an auxiliary guide 23' is used in connection with one of the guides 23 for a narrow rear chisel. The guide 23' is provided with thumb-screws 62, which may be inserted in any one of a series of rows of openings 63, formed in the rear face of one or of both of the carriages 11 12.

While the construction herein described and illustrated is the preferred form of the device, it is obvious that many changes may be made in the form, proportions, size, and minor details of construction without departing from the spirit or sacrificing any of the advantages of my invention.

It will be noted that the plates 42' and 50 are adjustably connected by the thumb-screws 51, and in order to provide for a movement of both plates toward and from the vertical cutting-chisels to provide for the cutting of a wide or narrow hinge-seat the brackets 42 are provided with longitudinal slots 60, and the plates 42' and 50 are provided with similar slots 61, arranged at each end of said plates. Through these several slots are passed screws 62, which may be loosened to permit of the movement of said plates toward and from the chisels, the screws being tightened to lock said plates in any desired position.

Having thus described my invention, what I claim is—

1. In a device of the class described, the combination with the parallel guiding-bars, of carriages adjustably disposed thereon, cutting knives or chisels carried by said carriages, a lower mortising cutter or chisel, a carriage therefor, and means for adjustably connecting said carriage to the main carriages, substantially as specified.

2. The combination in a hinge-gainer, of the parallel carrying-bars, oppositely-disposed carriages adjustably mounted on said bars, end chisels or cutters supported and guided by said carriages, rearwardly-extending guides adjustably secured to said carriages, and a rear knife or chisel adapted to said guides, substantially as specified.

3. The combination in a gaining-machine, of the parallel guiding-bars, carriages adjustably mounted on said bars, chisel-carrying bars adapted to guides in said carriages, chisels carried by said bars, and springs normally tending to maintain said bars in an elevated position, substantially as specified.

4. The combination in a gaining-machine, of the parallel guiding-bars, a pair of tool-carriages adjustably mounted on said bars, chisels carried by said tool-carriages, rearwardly-extending guides adjustably secured to said carriages, an auxiliary guide adapted to be secured to one of said carriages, and a knife or chisel adapted to said guide, substantially as specified.

5. The combination in a gaining-machine, of the adjustable carriages, chisels carried thereby, and adjustable scale-bars mounted on the opposite ends of said carriages, substantially as specified.

6. The combination in a gaining-machine, of adjustable carriages, horizontally-disposed parallel plates adapted to said carriages, the lower surface of the upper plate being provided with a series of guiding-notches, and a mortising-chisel having inclined edge portions adapted to said notches, substantially as specified.

7. The combination in a gaining-machine, of the adjustable carriages, a pair of guiding-plates arranged in a plane below said carriages, a mortising-chisel carried by said plates, a carrying-bar secured to said plates, guiding-boxes adjustably mounted on the carriages and adapted to receive said carrying-bar, and means for adjusting said boxes, substantially as specified.

8. The combination in a gaining-machine, of the adjustable carriages, a vertically-disposed adjustable plate carried by one of said

carriages, a pair of guiding-plates arranged in a plane below said carriages, a mortising-chisel guided between said plates, and means for adjustably securing said plates to the vertically-disposed plate, substantially as specified.

9. The combination in a gaining-machine, of the parallel guiding-bars, a pair of tool-carriages adjustably mounted on said plates, slotted brackets 42 supported from said carriages, a pair of guiding-plates arranged in a plane below said carriages and provided with slots at each end, screws passing through the slots in said bracket and plates and adapted to confine the same in an adjusted position, and a mortising-chisel carried by said plates, substantially as specified.

In testimony that I claim the foregoing as my own I have hereto affixed my signature in the presence of two witnesses.

RICHARD BRYANT WARD.
